P. C. Ingersoll.

UNITED STATES PATENT OFFICE.

P. C. INGERSOLL, OF GREEN POINT, NEW YORK.

IMPROVEMENT IN HOOP-LOCKS FOR SECURING THE ENDS OF METALLIC BANDS.

Specification forming part of Letters Patent No. 23,249, dated March 15, 1859.

To all whom it may concern:

Be it known that I, P. C. INGERSOLL, of Green Point, in the county of Kings and State of New York, have invented a new and Improved Hoop-Lock for Securing Together the Ends of Metal Bale-Hoops; and I do hereby declare that the following is a full, clear, and exact description of the same, reference being had to the annexed drawings, making part of this description, in which—

Figure 1 is a longitudinal section of my invention, taken in the line $x x$, Fig. 3; Fig. 2, a transverse section of the same, taken in the line $x x$, Fig. 1; Fig. 3, an outer face view of the same; Fig. 4, an inner face view of the same; Fig. 5, an edge or side view of the same.

Similar letters of reference indicate corresponding parts in the several figures.

This invention consists in the employment or use of a metal loop in connection with a metal key, so arranged or formed and fitted within the loop as to securely lock, when properly adjusted, the ends of the hoop in the loop, as hereinafter fully shown and described.

To enable those skilled in the art to fully understand and construct my invention, I will proceed to describe it.

A represents a metal loop, which may be of ordinary gray or cast iron. This loop may be described as being composed of the side pieces $a a$, connected by end pieces, $b b'$, one end piece, b , being near the inner, and the outer end piece, b' , near the outer side of the loop, as shown clearly in Fig. 1.

B represents what I term the "key," which is also of ordinary gray or other cast iron, and of bent form, it having two plates, $c c'$, connected by an oblique or central portion, d , as shown clearly in Fig. 1. The key B, when fitted in the loop A, has one plate, c , fitting against the outer side of the end piece b , and the other plate, c' , fitting against the inner side of the end piece b , as shown clearly in Fig. 1, the oblique central portion, d , compensating for the relative position of the end pieces, $b b'$, of the loop.

At the outer end of the plate c of the key B there are two hook-shaped projections, $e e$, one at each side, and these projections, when the key is in the loop, fit over oblique or beveled ends f of the sides $a a$ of the loop, as shown clearly in Fig. 5. The outer end of the plate c' also expands laterally, so as to form a sort of

dovetail lock between the inner surfaces of the sides $a a$ of the loop, as shown clearly at c^* in Fig. 4.

The loop A and key B form the hoop-lock, and it is used or applied as follows: The iron hoops are adjusted in the box of the press, as usual, and when the material is compressed the ends of the hoops are fastened in the loops A. The end g of a hoop, for instance, is bent around the end piece b' of the loop, as shown clearly in red, Fig. 1, and the opposite end, h , is bent around the end piece b . The key B is then snugly fitted in position, the plate c of the key bearing against the end of the loop at the inner side of the end piece b' , and the plate c' bearing against the end b on the end h of the hook, the hooks $e e$ of the plate b being fitted over the oblique ends f of the sides $a a$ of the loop, and the outer end of plate c fitted between the outer oblique portions of the sides $a a$. The end h of the hoop is then bent around and over the outer side of plate c , and passed a short distance between the plate c and the end g of the hoop around the end piece b' , as shown in red, Fig. 1.

From the above description it will be seen that a very simple and efficient hoop-lock is obtained. It may be very readily applied, and the key is prevented from being casually loosened in consequence of the hook-shaped projections $e e$ fitting over the oblique ends f of the sides $a a$ of the loop, and the expanded outer end, c' , of the key B fitting between the opposite dovetail ends of the sides $a a$, the strain or pull of the hoop, as well as the bent end h of the hoop, favoring the keeping or securing of the key in proper place or position. The outer surface of the plate c of the key B has ledges $i i$, one at each side, as shown more particularly in Figs. 2 and 3, in order to prevent the end h of the hoop from slipping laterally off the plates c .

Having thus described my invention, what I claim as new, and desire to secure by Letters Patent, is—

The loop A and key B, fitted together and applied to the hoop, substantially as and for the purpose set forth.

P. C. INGERSOLL.
